CLAIM

The ornamental design for a combined bactericidal ozonic air cleaner and cover therefor, as shown.

DESCRIPTION

FIG. 1 is a front-right-top perspective view of a combined bactericidal ozonic air cleaner and cover therefor with the cover removed for clarity of illustration, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view similar to FIG. 1, but further showing a cover which shelters an opening which is defined in a top panel thereof; and,

FIG. 9 is a front view similar to FIG. 2, but further showing a cover which shelters an opening which is defined in as top panel thereof.
